TOILET STRUCTURE FOR BATHROOMS
OR THE LIKE

Landrum E. Bagwell, Brevard, N. C.

Application May 11, 1943, Serial No. 486,562

9 Claims. (Cl. 4—2)

My invention relates to a toilet structure for bath rooms or the like.

An important object of the invention is to provide a toilet structure of the above mentioned character, wherein a bath tub, flush tank, lavatory bowl, and commode bowl are assembled to provide a unit, which is compact and convenient in use.

A further object of the invention is to provide a fixture unit which may be securely attached to the tub and the commode bowl, and which will avoid manufacturing hazards.

A further object of the invention is to provide a fixture unit of the above mentioned character, which will support the flush tank and lavatory bowl unit.

A further object of the invention is to provide a fixture unit of the above mentioned character, which will provide a counter vent and will meet the requirements of plumbing codes throughout the country.

A further object of the invention is to provide a fixture unit of the above mentioned character, which may be used in connection with right or left tubs, and will also provide clean-out plugs.

A further object of the invention is to provide a fixture unit of the above mentioned character, having a trap which is common to the drain of the commode bowl, the overflow of the tub, and the drain of the lavatory bowl.

A further object of the invention is to provide a fixture unit of the above mentioned character, which is of simple construction, strong, and may be readily applied in place.

A further object of the invention is to improve upon the construction of the toilet structure shown in Patent 2,009,756, granted to me under date of July 30, 1935.

Other objects and advantages of my invention will be apparent during the course of the following description.

In the accompanying drawings, forming a part of this application and in which like numerals are employed to designate like parts throughout the same,

Figure 1 is a side elevation of the foot end of the tub, lavatory bowl, flush tank and commode bowl, parts broken away, and parts in vertical section.

Figure 1^a is a transverse section taken on line 1^a—1^a of Figure 1.

Figure 2 is an end elevation of the combined tub, lavatory bowl and fluid tank, with the commode bowl removed, parts broken away,

Figure 3 is a front elevation of the fixture unit, and

Figure 4 is a horizontal section taken on line 4—4 of Figure 1, parts broken away.

In the drawings, wherein for the purpose of illustration is shown a preferred embodiment of my invention, the numeral 10 designates a tub, having a skirt 11 extending down to the floor. This tub is of the usual size for bathing and includes a foot portion having a vertical end wall 12, and an inclined lower portion 13.

A unit or casting is provided including a flush tank 14 and a lavatory bowl 15, and this unit is mounted above and upon the foot end of the tub 10, and extends longitudinally beyond the same. This unit includes a depending skirt 16, engaging with or supported by the upper edge of the tub. The outer side of the skirt 16 is cut away, providing an opening 16', covered by a door 17.

I provide a fixture unit 17 comprising an upper flush pipe 18 and a lower drain pipe 19. The pipe 18 has a curved portion 20 and the pipe 19 has a curved portion 21, and these curved portions are preferably formed integral with each other and with a flange or disk 22, and reenforcing webs 22' and 23', as shown. The opening of the curved portion 20 and the opening of the curved portion 21 extend through the face of the flange 22, as shown. The fixture unit 17 further comprises a trap 23, arranged upon the forward side of the vertical drain pipe 19, and preferably formed integral therewith. This trap is arranged beneath the inclined bottom portion 13 of the tub. This trap includes a partition or web 24, to provide a water seal, and the trap has communication with the interior of the drain pipe 19 through an opening 25. Tubular bosses 26 and 27 lead into the bottom of the trap, upon its opposite sides and beneath the partition 24,

while tubular bosses 28 and 29 lead into the top of the trap, upon its opposite sides, rearwardly of the partition 24, and above the opening 25. Formed integral with the intake or forward end of the trap 23 is a tubular horizontal arm 30, having openings 31 in its top and bottom. Formed integral with the vertical flush pipe 18, near its upper end, are horizontal rods or lugs 32, diametrically oppositely arranged.

The vertical end wall 12 of the tube is provided at its top with downwardly facing hooks 33, rigidly secured thereto, and these hooks receive therein the lugs 32, and securely attach the upper end of the flush pipe with the tub. The spud end or tubular extension 34 which is rigidly secured to the bottom of the flush tank and through which

the water discharges from the flush tank, extends into the upper end of the flush pipe 18. There is a clamping nut 35, having screw threaded engagement with the tubular extension 34, and clamping a cork washer to the upper end of the flush pipe 18, for forming a gas tight joint. At its bottom, adjacent to the wall 13, the tub has a tubular drain cage 37 in its drain opening and this drain cage has its top flanged and the cage extends through the openings 31 in the tubular arm 38 and has openings 38 for the escape of the water into the tubular arm 39. The top of the cage is open while its bottom is closed and the lower portion of the cage is threaded, at 39, for receiving a clamping nut 40. The cage therefore serves to rigidly attach the tubular arm with the bottom of the tub.

The numeral 41 designates a commode bowl, arranged transversely of the tub and having a flange 42, secured to the flange 22 by bolts 43. This bowl has a partition 44 forming a water seal or trap, and a water inlet 45 for receiving the water from the flush pipe 18.

The tubular boss 26 has its screw threaded plug removed and receives therein one end of the drain pipe 46, which leads to the overflow 47 of the tub, and has connection with a drain pipe 48, leading to the drain 49 of the lavatory bowl 15. The companion tubular boss 27 has its screw threaded plug 50 held therein. The screw threaded tubular boss 28 has its plug 51 held therein, while the corresponding plug is removed from the tubular boss 29 and a cross vent pipe 52 leads into the tubular boss 29.

At its bottom, the fixture unit is belled, as shown at 53, and has a groove 54, for putty or packing, as ordinarily employed in stool installation. The flush tank 14 is provided with the usual flush valve or ball to control the passage of water through the flush pipe 18, the bowl 15 has the usual drain valve, and the tub the usual overflow outlet. The usual means are employed to supply water to the flush tank, lavatory bowl and tub.

The fixture unit is illustrated as applied to a left tub. The fixture unit may also be applied to a right tub, in which event the fixture unit would be reversed, the pipe 46 would be connected with the tubular boss 27 and the tubular boss 26 closed, while the pipe 52 would be connected with the tubular boss 28 and the tubular boss 29 closed. The plugs 50 and 51 may also serve as clean-out plugs, as they may be removed to provide openings leading to the trap.

It is thus seen that the fixture unit is securely attached to the tub at the top and bottom of the tub, and its lower end rests upon the floor, and will securely support the commode bowl and the flush tank and lavatory bowl unit, from the floor. The fixture unit will also support the rear end of the lavatory bowl and flush tank unit. Since the trap 23 is common to the drain of the lavatory bowl and the overflow of the tub, one trap is eliminated, as two traps are ordinarily employed.

It is to be understood that the form of my invention herewith shown and described is to be taken as a preferred example of the same, and that various changes in the shape, size, and arrangement of parts, may be resorted to, without departing from the spirit of my invention or the scope of the subjoined claims.

Having thus described my invention, what is claimed is:

1. In a toilet structure; a tub having a drain

opening in its bottom and an overflow; a flush tank and lavatory bowl mounted upon the tub near the drain opening; a fixture unit including an upper flush pipe, a lower drain pipe, a flange connecting the adjacent inner ends of such pipes, a trap arranged upon one side of the drain pipe and secured thereto and discharging into the drain pipe, and a tubular arm connected with the trap and having openings in its top and bottom, the bottom of the fixture being adapted to rest upon the floor; a tubular cage mounted within the drain opening of the tub and extending through the openings in the top and bottom of the tubular arm and serving to connect the tubular arm with the bottom of the tub; a commode bowl having a trap and a flange attached to the first named flange; a drain pipe for the lavatory bowl; an overflow pipe for the tub, said overflow pipe being connected with the lavatory bowl drain pipe and leading into the lower portion of the trap; and a vent pipe leading into the top of the trap, said vent pipe serving to vent the trap and the drain pipe of the commode bowl.

2. In a toilet structure; a tub having a drain opening in its bottom and an overflow; a flush tank and lavatory bowl mounted upon the tub near the drain opening; a fixture unit including an upper flush pipe, a lower drain pipe, a flange connecting the adjacent inner ends of such pipes, a trap arranged upon one side of the drain pipe and secured thereto and having its upper portion in communication with the drain pipe, and a tubular arm connected with the trap and having an opening in its top, the bottom of the fixture unit being adapted to rest upon the floor; a tubular cage mounted within the drain opening of the tub and extending through the opening in the top of the tubular arm and serving to connect the tubular arm with the bottom of the tub; means for attaching the upper portion of the flush pipe with the tub; a commode bowl having a trap and a flange attached to the first named flange; an overflow pipe for the tube leading into the lower portion of the trap; a drain pipe for the lavatory bowl leading into the overflow pipe; and a vent pipe leading into the top of the trap, said vent pipe serving to vent the trap and the drain pipe of the commode bowl.

3. In a toilet fixture; a tub having a drain opening in its bottom and an overflow near its end; downwardly facing spaced hooks secured to said end of the tub near its top; a flush tank and lavatory bowl mounted upon the tub near the drain opening; a fixture unit including an upper flush pipe for the flush tank, a lower drain pipe for a commode bowl, a flange connecting the adjacent inner ends of such pipes, a trap arranged upon one side of the drain pipe and secured thereto and having its upper portion in communication with the drain pipe, a tubular arm connected with the upper portion of the trap and having an opening in its top, lugs secured to the upper end of the flush pipe to engage within the hooks, the bottom of the fixture unit being adapted to rest upon the floor; a tubular cage mounted within the drain opening of the tub and extending through the opening in the top of the tubular arm and serving to connect the tubular arm with the bottom of the tub; a commode bowl having a trap and a flange attached to the first named flange, the commode bowl receiving water from the flush pipe and discharging water through the drain pipe; an overflow pipe for the tub leading into the lower portion.

of the trap; a drain pipe for the lavatory bowl leading into the overflow pipe; and a vent pipe leading into the upper portion of the trap, said vent pipe serving to vent the trap and the drain pipe of the commode bowl.

4. A fixture unit comprising an upper flush pipe and a lower drain pipe having their inner ends connected and their bores separate, lugs carried by the flush pipe, a trap secured to the drain pipe and having communication with the drain pipe above the liquid level of the trap, a tubular arm connected with the trap and to be connected with a drain, means for connecting a vent pipe with the upper portion of the trap and next to the drain pipe, and means for connecting a pipe with the lower portion of the trap beneath the liquid level therein.

5. A fixture unit comprising an upper flush pipe and a lower drain pipe having laterally extending inner adjacent ends which are connected, the bores of the laterally extending ends being separate, an attaching flange secured to such inner ends, lugs carried by the upper portion of the flush pipe, a trap secured to the vent pipe and having communication with the vent pipe through an opening disposed above the level of the liquid within the trap, a tubular arm connected with the upper portion of the trap and arranged remote from said opening, tub connecting means secured to the tubular arm, said trap being provided in its upper portion and next to the drain pipe with an opening for a vent pipe and in its lower portion with an opening for a water supply pipe.

6. A fixture unit comprising an upper flush pipe and a lower drain pipe having their inner ends connected and their bores separate, a commode bowl connecting means for such inner ends, a top connecting means for the flush pipe, a trap secured to the drain pipe and having communication with the drain pipe through an opening arranged above the level of the liquid within the tank, a tub connecting means for the end of the trap remote from the drain pipe, said trap being provided in its upper portion next to the drain pipe with an opening for a vent pipe and in its lower portion with an opening for another pipe.

7. A fixture unit for use in connection with a tub having a drain opening in its bottom and an overflow, a flush tank and lavatory bowl mounted upon the tub near the drain opening, and a commode bowl having a trap and an attaching flange and a flush opening and a drain opening, said fixture unit comprising an upper flush pipe, a lower drain pipe, a flange connecting the adjacent ends of such pipes, a trap arranged upon one side of the drain pipe and secured thereto and discharging into the drain pipe, and a tubular arm connected with the trap and having open-

ings in its top and bottom, a tubular cage to be mounted within the drain opening of the tub and extending through the openings in the top and bottom of the tubular arm and serving to connect the tubular arm with the bottom of the tub, the flange of the fixture unit being adapted to engage with the flange of the commode bowl, means to secure the flange of the fixture unit to the flange of the commode bowl, a pipe leading into the lower portion of the trap and adapted for connection with the overflow of the tub and the drain of the lavatory bowl, and a vent pipe leading into the top of the trap, said vent pipe serving to vent the trap and said drain pipe, the lower end of the fixture unit resting upon the floor to be supported thereby.

8. A fixture unit comprising an upper flush pipe and a lower drain pipe arranged in end-to-end relation and having their inner ends extending laterally and separate, said flush pipe and drain pipe being rigidly connected, attaching means secured to the inner ends of the flush pipe and drain pipe, a trap arranged upon one side of the drain pipe and rigidly secured to the same and discharging into the drain pipe at an elevation above the level of the liquid within said trap, a tubular arm connected with the trap and having openings in its top and bottom, a tubular cage for insertion within the openings in the top and bottom of the tubular arm, said trap having means in its lower portion for connection with an overflow pipe and means in its top for connection with a vent pipe, the vent pipe serving to vent the trap and the drain pipe, the bottom end of the vent pipe and trap being arranged to rest upon the floor to be supported thereby.

9. A fixture unit comprising a vertical body portion having its lower end adapted to rest upon the floor, said body portion comprising an upper flush pipe and a lower drain pipe which are rigidly connected and have separate openings at their inner ends, lugs secured to the flush pipe, a trap arranged upon one side of the drain pipe and rigidly secured thereto, the drain pipe having an opening leading into the trap at an elevation above the level of the liquid within the trap, said trap having a pipe connection leading into its lower portion below the liquid level therein, said trap having a pipe connection leading into its upper portion above the level of the liquid therein, the last named pipe connection being arranged next to the drain pipe, and a generally horizontal tubular arm secured to the trap and leading into the trap above the level of the liquid therein and upon the side thereof remote from the opening between the drain pipe and trap, said tubular arm having an opening formed in its top to receive a coupling.

LANDRUM E. BAGWELL.
